UNITED STATES PATENT OFFICE.

LORENZ IVERSEN, OF PITTSBURGH, PENNSYLVANIA.

METHOD OF MAKING VALVES.

Application filed January 23, 1924. Serial No. 687,971.

The present invention relates broadly to the method of making valves, and more particularly to valves of the character adapted for use with fluid pumps and compressors.

5 In valves of the type to which the present invention relates, it is desirable to provide a valve spring of such construction that it is adapted to effectively resist lateral deflection, and a valve plate detachably secured thereto whereby either the valve plate or the 10 spring may be individually renewed as found necessary.

In the accompanying drawings, there is shown, for purposes of illustration only, a 15 preferred embodiment of the present invention, it being understood that the drawings do not define the limits of the invention, as changes in the construction and operation 20 therein disclosed may be made without departing from the spirit of the invention or scope of my broader claims.

In the drawings:

Figure 1 is a top plan view, partly broken away, of a completed valve;

25 Figure 2 is a transverse sectional view on the line II-II of Figure 1;

Figure 3 is a vertical sectional view through a set of forming dies showing a blank in position for the first forming step;

30 Figure 4 is a view similar to Figure 3, illustrating a second set of forming dies adapted to perform a second forming operation on the partly shaped blank; and

Figure 5 is a view similar to Figure 3 through a third set of forming dies illustrating the final forming operation.

Certain features of the valve structure herein disclosed have been made the subject matter of my copending application, 40 Serial No. 687,970, filed of even date herewith.

In carrying out the present invention, there may be provided a valve spring 2, of rectangular cross section, being preferably constructed of thin flat metal having a sufficient cross sectional area in a direction at substantially right angles to the axis of the spring to effectively resist lateral deflection. The spring is preferably of tapered outline, 45 comprising a series of nesting convolutions with the end convolutions substantially flat. The larger end convolution 3 is preferably formed to provide a continuous substantially circular outer surface, adapted to cooperate 50 with a valve plate 4, which may be advantageously formed into position therearound,

as hereinafter more fully pointed out. This form of valve spring may be easily formed by simply cutting a circular body of material along a spiral line, starting and finishing within said body.

In Figure 3 of the drawings, there is illustrated a pair of dies, one of which is formed with a recess 5, adapted to receive the other. In the first operation, there is placed across 65 the recessed die a body of material from which a valve body is formed, this body preferably being in the form of an annulus A. The male die is then brought into co-

operative engagement with the annulus to 70 press it into the recess 5, as clearly shown in Figure 4, and form a cup-shaped blank having an upturned peripheral edge 6. This blank at the conclusion of the first forming

operation may be retained in the recessed 75 forming die or may be transferred therefrom into a second die of similar construction. There is then placed within this blank the larger end convolution 3 of a valve 80 spring of the character before described. 80

The outer diameter of this end convolution may be slightly smaller than the internal diameter of the blank, but it is preferably substantially equal thereto. The continuous 85 outer surface of the larger end convolution bears against the upturned edge 6. There-

after this edge may be subjected to the action of a die 7 effective for slightly turning the edge inwardly into a position substantially as illustrated in Figure 5. A suitable die 8 90

may then be brought into cooperative engagement with the partially inturned edge to bend the same inwardly around the larger 95 end convolution of the spring. Due to the continuous and uniform support provided by the end convolution 3, the edge 6 bends in smoothly and evenly, and firmly clamps

the spring in position. The greater the pressure exerted in completing the bending in 100 of the edge 6, the tighter will be the union between the spring and valve plate.

While I have described the method of forming a plate about a spring by the use of dies, it will be understood that by reason of the continuous surface provided by the 105 end convolution 3, the same results may be accomplished by spinning as well understood in the art.

The advantages of the present invention arise from the provision of a method of 110 making valves in which the spring has the property of resisting lateral deflection and is

so shaped that a continuous and uniform bearing or engaging surface is provided between the valve spring and the valve plate, and in which the plate is removable as may be required.

I claim:

1. The method of making valves, which comprises cupping a blank to form a peripherally extending flange thereon, inserting the end convolution of a spring into position within said flange, and then bending the flange inwardly around said convolution, substantially as described.
2. The method of making valves, which comprises cupping an annulus to form a continuous peripheral flange thereon, inserting the end convolution of a tapered spring into position within said flange, and then bending the flange inwardly around said convolution, substantially as described.
3. The method of making valves, which comprises cupping a blank to form a peripheral flange thereon, inserting the end convolution of a tapered spring into position within said flange, and then bending the flange inwardly into substantial parallelism with the bottom of the cupped annulus and uniformly supporting the blank by the end convolution during the bending operation, substantially as described.
4. The method of making circular valves, which consists in cupping a blank to form a peripheral flange thereon, inserting the larger end convolution of a tapered spring within said flange, bending said flange inwardly, and then further bending said flange around said end convolution to form a continuous clamping engagement between the spring and the bent flange, substantially as described.
5. The method of making valves, comprising forming a spring of substantially rectangular metal having nesting convolutions and of sufficient cross sectional area in a direction at right angles to its axis to resist lateral deflection, partially forming an annulus, placing the partially formed annulus and spring in cooperative engagement,

and forming the edge of the annulus around one of the convolutions of the spring and uniformly supporting the annulus by the spring during such forming operation, substantially as described.

6. In the method of making valves, the steps consisting in forming a blank and a tapered spring, bringing the larger end convolution of the spring into engagement with the blank, and forming the blank around said convolution while supporting the blank by the spring, substantially as described.

7. The method of making valves, comprising forming a spring of relatively thin flat metal having nesting convolutions and of sufficient cross sectional area in a direction at right angles to its axis to resist lateral deflection, partially forming an annulus, placing the partially formed annulus and spring in cooperative engagement, and bending the edge of the annulus around one of the convolutions of the spring while supporting the annulus by the spring, substantially as described.

8. In the method of making valves, the steps consisting in forming a blank and a spring, bringing one end convolution of the spring into engagement with the blank, and forming the blank around said convolution while supporting the blank by such end convolution; substantially as described.

9. In the method of making valves, the steps consisting in forming an annulus and a tapered spring, bringing the larger end convolution of the spring into engagement with the annulus, and bending the annulus around the outer edge of said convolution, substantially as described.

10. In the method of making valves, the steps consisting in forming a spring having one end convolution shaped to provide a substantially continuous surface, bringing said end convolution into engagement with a blank, and then bending the blank around said convolution, substantially as described.

In testimony whereof I have hereunto set my hand.

LORENZ IVERSEN.
